HONING TOOL

Carl F. High, Flint, Mich.

Application November 27, 1933, Serial No. 699,843

13 Claims. (Cl. 51—184.1)

More particularly the invention relates to a rotary honing tool adapted for finishing bores of relatively small diameters, with extreme accuracy.

5 The finishing of small holes, such for example as are used for cylinder bores in small pumps, presents a distinct problem because of the fact that it is necessary to hold the tolerance of holes, as small as one-quarter inch in diameter, to a 10 straightness, roundness and smoothness of less than one-tenth of one-thousandth of an inch, and furthermore, on a production basis, it is necessary to hold the cost of the finishing operation down to a very small amount per hole. It is 15 an object of the invention to provide a new and improved honing tool adapted to finish such small diameter bores with the desired accuracy.

Another object is to provide a rotary honing tool embodying new and improved means for 20 forcing the stones outwardly against the wall of the bore being finished so as to provide a uniform pressure of the stones against the work throughout the length of the stones.

Another object is to provide a new and improved honing tool comprising a supporting member having a cylindrical portion of a diameter to provide a running fit in the bore to be finished, together with a plurality of stones mounted on said supporting member for movement outwardly into engagement with the wall 30 of the bore.

Another object is to provide a rotary hydraulically operated honing tool embodying means for utilizing a portion of the fluid to centralize the pressure on a rotating stone supporting member.

Another object is to provide a rotary hydraulic honing tool wherein fluid under pressure for expanding the stones flows through the tool and into the bore being finished, and serves as a cooling medium for the stones and also serves to wash out the material removed.

Further objects will become readily apparent from the following detailed description, taken in connection with the accompanying drawing, in which:

Fig. 1 is a longitudinal central section through a honing tool, shown connected to a pressure fluid supply.

Fig. 2 is a section along the line 2—2 of Fig. 1.

Fig. 3 is a section along the line 3—3 of Fig. 1.

Fig. 4 is a fragmentary view, partly in central section, of a modified form of honing tool.

Fig. 5 is a section along the line 5—5 of Fig. 4.

For purposes of disclosure I have illustrated in 55 the drawings and shall hereinafter describe in

detail a preferred embodiment of the invention together with a modified form thereof, with the understanding that I do not intend to limit the invention to the particular construction and arrangement shown, it being contemplated that various changes may be made by those skilled in the art without departing from the spirit and scope of the appended claims.

In the form illustrated in Figs. 1 to 3, the invention comprises a rotary supporting member 10 having a cylindrical portion 10' adapted for insertion into the bore of the work piece. Preferably the cylindrical portion 10' is of a diameter providing a running fit in the bore to be finished and has an elongated diametrically extending recess 11 intermediate its ends. This recess is shown as having a straight wall 12 at its lower end, an upper wall with beveled surfaces at 13 and 14, and straight parallel sides 15 and 16. A pair of elongated stones or hones 17 and 18 are slidably mounted in the recess 11 for movement radially of the rotary member 10. Preferably the stones have parallel side surfaces so as to slide like pistons in the recess 11, the recess, in effect, forming a pair of radially extending cylinders. As illustrated, the hones are beveled at their ends, the upper ends being beveled to correspond with the beveled surfaces of the end wall of the recess. At its lower end the rotary member 10 has a portion 20 of reduced diameter on which a tubular bushing 21 is slidably mounted. At its upper end said bushing has an outwardly flared annular flange 22 the upper edge of which engages the beveled lower ends of the hones 17 and 18. The bushing is normally urged upwardly into engagement with the hones by means of a coiled spring 23 positioned intermediate the lower end of the bushing and a split ring 24 (Figs. 1 and 3) secured in an annular groove in the portion 20. As illustrated in Fig. 1, the upward movement of the bushing is limited by the engagement of a conical surface 25 on the bushing flange 22, with a corresponding conical surface 26 on the rotary member 10.

The hones 17 and 18 are thus normally retained in the recess 11 by means of the beveled surfaces 13 and 14 on the upper end wall of the recess and the spring pressed bushing 21. A curved spring 27 is preferably provided intermediate the hones so as to hold them yieldably in extended positions as determined by the limiting surfaces 25 and 26.

As illustrated herein the upper end of the rotary member 10 is secured to one end of a 55

tubular flexible coupling 30, the other end of which is secured to the lower end of a tool shank 31. The shank 31 is rotatably mounted in a non-rotatably supported member 32 and extends upwardly therethrough so that its upper end 31' may be secured in a suitable chuck, for example, on a drill press or other machine tool whereby the shank and the member 10 carried thereon may be given a rotary movement, as well as a vertical oscillatory movement. The member 32 is preferably provided with a port 33 adapted for connection to one end of a suitable conduit 34, the other end of which is connected to a supply of a fluid under pressure, the fluid being adapted to pass through the port 33 to an annular chamber 35 formed in the member 32 surrounding the shank 31. From this chamber the fluid passes through a radial port 36 in the shank and an axial port 37 therein, then through the flexible coupling 30 and an axial passage 38 in the rotary member 10, the lower end of which passage communicates with the central portion of the recess 11. In this manner fluid supplied through the conduit 34 is conducted into the space between the hones 17 and 18 so that it may act directly against the inner surfaces of the hones and force them outwardly into engagement with the work.

In the exemplary form of the invention the conduit 34 is connected, through a valve 40, to the lower portion of a fluid supply tank 41. The upper portion of the tank is connected by means of a pipe 42 and a valve 43 to a suitable air supply conduit 44. The valve 43 is preferably included for the purpose of controlling the pressure of the air admitted to the tank, a gage 45 being provided for indicating the pressure of the air in the line 44. A gage 46 indicates the pressure within the tank. By this means the pressure of the fluid supplied to the tool may be adjusted and may be kept constant at any desired value.

The fluid used may be kerosene or any other liquid found suitable for the type of stones and the material being finished. Preferably the fluid is used not only to exert a working pressure on the hones, which pressure is adjustable and controllable, and distributed and uniform throughout the length of the hone, but also to centralize the pressure on the rotating member and to wash out the material being removed from the work. To this end the rotary member 10 is preferably provided with flat portions 50 on its periphery intermediate the stones, and ports 51 connecting the cavities formed by the flat portions with the recess 11. Fluid passes out from the recess into the space surrounding the rotary member so as to wash out the removed material, and also so as to exert equal pressure on opposite sides of the member 10 to centralize said member. With a running fit of the cylindrical portion of the supporting member in the bore being finished, the discharge of fluid is somewhat restricted, permitting the proper pressure to be maintained on the stones. A tool for finishing $\frac{1}{8}$ " diameter bores, and provided with a plurality of stones has operated efficiently with a running fit clearance of approximately .0006 of an inch and a fluid pressure of about 80 pounds per square inch. In addition to these functions of the fluid, the fluid serves as a means for cooling the hones, the direct contact of the fluid with the hones along their entire inner surfaces and the flow of fluid through the tool greatly facilitating this cooling action.

In the form illustrated in Figs. 4 and 5, a

rotary member 10" is provided with a recess 11' which extends radially from an axial passage 38', a single stone 18' being provided. In this form of the invention flat spots 50' on the periphery of the member are supplied with fluid under pressure through ports 51', the flat spots and stone being spaced apart equally around the member. 5

In use, as mentioned hereinbefore, the tool is mounted by means of the shank 31 in the chuck of a suitable machine so that the tool may be rotated and at the same time oscillated axially. When the cylindrical stone carrying portion of the tool operates with a running fit in the bore being finished the clearance between the supporting member and the wall of the bore is quite 15 small, so that the stones project but a slight distance from the member 10. In operation, therefore, the stones are retracted from the positions illustrated in the drawing. The spring 27 serves merely to hold the stones in initial engagement with the bore being finished, the pressure of the spring and also the centrifugal force on the stones when rotating being inadequate to provide a cutting pressure. The cutting pressure is obtained by means of the fluid acting 20 against the inner surfaces of the stones, the stones themselves acting as pistons. As the pressure on the stones regulates the speed of cutting, this may be varied for stones of different hardness 25 and for different classes of work. For a given type of stone and a given class of work the amount of material removed from the wall of a bore is a function of the pressure of the stones against the wall, and the length of time the stones are in contact with the wall. With a construction such as illustrated herein, wherein means is provided for adjusting and maintaining the pressure of the fluid against the stones, the bores in a plurality of work pieces may be finished to close limits of uniformity by maintaining the 40 stones in contact with the work for a predetermined number of revolutions of the tool. 35

I claim as my invention:

1. A rotary honing tool comprising, in combination, a supporting member having a cylindrical portion of a diameter providing a running fit in the hole to be finished, and having a diametrically extending recess provided with parallel side walls, a pair of stones positioned in said recess for movement radially therein, said member having a passage for supplying fluid under pressure to said recess between said stones so as to urge the stones outwardly into engagement with the work, and a port leading to the periphery of the member discharging the fluid under pressure to the bore being finished. 45

2. A rotary honing tool comprising, in combination, a supporting member having a cylindrical portion of a diameter providing a running fit in the hole to be finished, and having a diametrically extending recess provided with parallel side walls, and a pair of elongated stones positioned in said recess for movement radially therein, said member having a passage for supplying fluid under pressure to said recess between said stones so that the fluid exerts an expanding pressure throughout the length of the stones and urges the stones outwardly into engagement with the work. 60

3. A honing tool comprising, in combination, a supporting member having a cylindrical portion of a diameter to provide a running fit in the bore of the tool is intended to finish, and a plurality of stones carried on said supporting member for movement outwardly into engagement with the 70 work. 75

- wall of the bore, said supporting member having radially extending recesses intermediate the ends of the cylindrical portion in which the stones are movably mounted, and a passage communicating with the radial recesses for supplying a fluid under pressure to the inner surfaces of the stones to urge the stones outwardly. 5
4. A honing tool comprising, in combination, a supporting member having a cylindrical portion of a diameter to provide a running fit in the bore the tool is intended to finish, and a stone carried on said supporting member for movement outwardly into engagement with the wall of the bore, said supporting member having a recess in 10 which the stone is movably mounted, and means for supplying a fluid under pressure to the inner surface of the stone to urge the stone outwardly. 15
5. A honing tool comprising, in combination, a supporting member adapted to be rotated and to be reciprocated longitudinally during a finishing operation, said supporting member having a stone receiving recess and cylindrical portions adjacent each end of said recess, adapted for a running fit in the bore to be finished, a stone 20 mounted in said recess for movement outwardly into engagement with the wall of the bore, and means for supplying fluid under pressure to said recess for urging said stone outwardly and for maintaining a predetermined uniformly distributed working pressure of the stone against the surface being finished. 25
6. A rotary honing tool comprising, in combination, a supporting member having a diametrically extending recess provided with parallel side walls, a pair of elongated stones positioned in said recess for movement radially therein, said member having a passage for supplying fluid under pressure to said recess between said stones so as to urge the stones outwardly like pistons 30 into engagement with the work, and ports leading to the periphery of the member intermediate the stones for discharging the fluid under pressure to the bore being finished. 35
7. A honing tool comprising, in combination, a rotary member having a recess intermediate its ends, a stone slidable in said recess for movement outwardly of said member, yieldable means for retaining said stone in said recess, and means for supplying fluid under pressure directly 40 against the inner surface of said stone so as to exert a working pressure on the stone against the work, and for discharging the fluid at a restricted rate into the bore being finished to wash out the material removed. 45
- 55 8. A honing tool comprising, in combination, a rotary member having a recess intermediate its ends, a stone slidable in said recess for movement outwardly of said member, yieldable means for retaining said stone in said recess, and means for supplying fluid under pressure directly 5 against the inner surface of said stone so as to exert a working pressure on the stone against the work. 5
9. A honing tool comprising, in combination, a rotary member, a stone mounted for movement outwardly of said member, and means for supplying fluid under pressure directly against the entire inner surface of said stone so as to exert a uniformly distributed working pressure on the stone against the work. 10
10. A honing tool comprising, in combination, a member having a recess therein, a stone fitted to slide in said recess like a piston and to project beyond the surface of the member for engagement with a work piece to be finished, and means for supplying pressure fluid to the inner end of said recess to urge the stone outwardly and to cool the stone. 15
11. A honing tool comprising, in combination, a rotary supporting member, a hone carried on said member for movement radially thereof, and means for moving said hone outwardly into engagement with a workpiece and for cooling the hone comprising a pressure fluid passage in said member for supplying fluid to the inner surface 20 of the hone, and a restricted outlet passage for the fluid so as to maintain a pressure against said hone and at the same time permit a constant flow of fluid through the supporting member. 25
12. A honing tool comprising, in combination, a rotary member having a radially extending recess therein, a stone fitted to move radially in said recess like a piston, and means for supplying pressure fluid to the inner end of said 30 recess to urge the stone outwardly. 40
13. A rotary honing tool comprising, in combination, a supporting member having a cylindrical portion of a diameter to provide a running fit in the bore the tool is intended to finish, and a plurality of elongated radially extending slots provided with parallel sides, a plurality of elongated stones slidably mounted in said slots for movement outwardly of said member, said member having a passage for supplying fluid under pressure to the inner surfaces of said stones, and a plurality of outlet ports for discharging fluid into the bore being finished so as to lubricate the bore and to wash away the material removed. 50
